[57] CLAIM

The ornamental design for a portion of a screen of a
programmed computer system or programmed facsimile
machine, as shown and described.

DESCRIPTION

FIG. 1 is a front elevational view of a portion of a screen of a
programmed computer system or programmed facsimile
machine showing a first embodiment of our new design; and,
FIG. 2 is a front elevational view of a second embodiment
thereof.

The broken-line disclosure of the unclaimed edge of the
screen portion is for illustrative purposes only and forms no
part of the claimed design.
